INVENTOR:

Robert Aernout Baron van Lynden

By *John Lotka*
ATTORNEY.

UNITED STATES PATENT OFFICE.

ROBERT AERNOUT BARON VAN LYNDEN, OF Utrecht, NETHERLANDS, ASSIGNOR, BY MESNE ASSIGNMENTS, TO AMERICAN THERMOPHONE COMPANY, OF BOSTON, MASSACHUSETTS, A CORPORATION OF MASSACHUSETTS.

Thermic Telephone.

1,312,504.

Specification of Letters Patent.

Patented Aug. 5, 1919.

Application filed May 2, 1916. Serial No 94,869.

To all whom it may concern:

Be it known that I, ROBERT AERNOUT BARON VAN LYNDEN, a subject of the Queen of the Netherlands, and residing at Utrecht, 5 in the Netherlands, have invented new and useful Improvements in Thermic Telephones, of which the following is a specification.

My invention relates to thermic telephones 10 and has particular reference to an improved construction of the heating conductors of such apparatus.

According to my invention the heating conductor is of such a nature that, unlike the 15 usual conductor of Wollaston or other wire, it is not capable of standing alone and it is laid, or preferably formed, upon a support which is a partial conductor of heat but is practically a non-conductor of electricity, 20 that is to say, the material forming the support, when used for this purpose, is sufficiently a non-conductor of electricity to prevent the short-circuiting of the heating conductor which is laid or formed upon it. 25 The support may be of any suitable material such for example as marble or other stone, china, porcelain or the like.

The heating conductor may be made in any convenient way, for instance it can be 30 formed of thin metallic sheet or foil laid upon the support to which it may be attached in intimate contact.

Again the conductor may be deposited electrolytically upon the support, the necessary figure or shape—for instance a loop or 35 series of loops—being deposited or a flat sheet or film of the requisite thinness being first deposited and the figure produced by etching out the portions not required.

Another method of making the conductor 40 according to my invention is to form the figure by drawing, painting or printing upon the support with a suitable metallic pigment or by tracing the figure upon the 45 support with a carbon, black lead or metallic pencil.

The heating conductor made according to my invention is generally broad in proportion to its thickness for it is intended to be 50 of extreme thinness and further the comparatively broad upper surface which is exposed to the air in the sound chamber, very quickly gives up its heat to that air. On the other hand the under surface, in intimate 55 contact with the support, which is a partial

conductor of heat, serves to prevent the heating conductor from accumulating heat and thus keeps practically constant what may be termed the normal working temperature of the apparatus.

In a modified construction also according to my invention the support for the heating conductor comprises a body of some material which is good conductor of heat, for instance a metal, and a thin layer or coating 65 of some material which is practically a non-conductor of electricity but a partial conductor of heat. Upon this surface or coating is laid, or preferably formed, the heating conductor itself.

It will be appreciated that the function of the thin layer or coating is to insulate electrically the heating-conductor while allowing its heat to be carried away rapidly by the heat-conducting body forming the main 75 portion of the support.

The layer or coating may be applied to or formed upon the body of the support in any convenient way, for instance the support may be made of metal and the layer or 80 coating may be produced by forming upon the surface, by chemical or other means, a film of oxid, sulfid or other compound which is sufficiently a non-conductor of electricity to prevent the short-circuiting of the 85 heating conductor when laid or formed upon it.

Another method consists in coating the metallic support with a thin layer of enamel, 90 varnish or the like of such a nature as to withstand the temperature to which the heating conductor is raised during the operation of the telephone. Or, again, a thin layer or sheet of some suitable material may be placed in intimate contact with the surface of the conducting body forming the 95 support.

In the accompanying drawings which are merely intended to illustrate the invention diagrammatically,

Figure 1 is an elevation with parts in section showing one construction of a thermic telephone according to my invention.

Fig. 2 is a plan showing the heating conductor resting upon its support, and

Fig. 3 is a vertical central section through a modified construction of support for the heating conductor also according to this invention.

Fig. 1 represents a thermic telephone 110

which in practice would usually be of small size so that it could be placed in the auditory passage of the outer ear. It comprises a tubular casing A which can be screwed on 5 to a connection cap B and holds down a sound chamber C which in its turn rests upon and secures in its place upon the connection cap the support D for the heating conductor.

- 10 In the usual construction of thermic telephones the heating conductor, made of Wollaston wire or the like, would be mounted so as to stand upright upon the support D, but according to this invention the conductor, 15 which is of such a nature that it cannot stand alone, is laid or formed upon the upper surface of the support D. In Fig. 2 the heating conductor is shown at E in the form of an S-shaped ribbon or strip of extreme thinness which is formed upon or laid upon the support D, its ends being secured in electrical contact with terminals or connections F, these being joined in any well-known or 20 approved manner with the leads G for connection to the circuit.

It will be understood that the heating conductor E may be of any shape or figure and may be formed upon the surface of the support D in any suitable way.

- 30 The support D shown in Figs. 1 and 2 is intended to be made of some material which is a partial conductor of heat but practically a non-conductor of electricity; a substance such as marble for instance might be employed.

In Fig. 3 a modified construction of support for the heating conductor is shown. In this case the main body of the support D¹ is 40 of metal and in order to avoid the short circuiting of the heating conductor E which would occur if it were laid or formed directly upon the metal surface, a thin layer or coating H is applied to or formed upon the surface of the support D¹ and on this 45 layer or coating H the heating conductor E is formed or laid, said coating H therefore forming the immediate support of the conductor E. As in the construction illustrated in Figs. 1 and 2 the ends of the heating 50 conductor E are joined to terminals F but these terminals must necessarily be insulated as they pass through the metallic block D¹. For this purpose insulating sleeves or bushes F¹ and insulating washers F² are provided.

The layer or coating H may be of any substance which is sufficiently a non-conductor of electricity as to prevent the short-circuiting of the heating conductor E and in some 60 cases the upper surface of the metal block D¹ may be tarnished heavily, for instance a coating of oxid or sulfid may be given which will suffice for the purpose.

I claim as my invention:

1. A thermic telephone comprising a heat 65 conductor and a support which is in contact with said conductor along substantially the entire length thereof, on one surface of the conductor, the remainder of the conductor's surface being exposed to the air, and the said 70 support being a partial conductor of heat but practically a non-conductor of electricity.

2. A thermic telephone comprising a heat 75 conductor and a support in contact with said conductor along substantially the entire length of the conductor, the said support being a partial conductor of heat but practically a non-conductor of electricity.

3. A thermic telephone comprising a sup- 80 port which is a partial conductor of heat but practically a non-conductor of electricity, and a heating conductor of such delicate na- 85 ture that it could not preserve its shape unsupported, said conductor, for substantially its entire length, being in contact with said support.

4. A thermic telephone comprising a sup- 90 port which is a partial conductor of heat but practically a non-conductor of elec- 95 tricity, and heating conductor of thin me- tallic foil in intimate contact with said sup- port.

5. A thermic telephone comprising a sup- 95 port which is a partial conductor of heat but practically a non-conductor of electricity, and a heating conductor formed of an elec- 100 trolytic deposit on said support.

6. A thermic telephone comprising a deli- 100 cate heating conductor and a support com- posed of a body which is a good conductor of heat, and a thin coating of a material which is a partial conductor of heat but practically a non-conductor of electricity, 105 said heating conductor being in surface con- tact with said coating.

7. A thermic telephone comprising a deli- 110 cate heating conductor and a support com- posed of a metallic body and a surface film of a material which will allow heat to pass 115 to said metallic body, but practically a non- conductor of electricity, said heating conductor being in contact with said film so that the heat from the conductor may pass through the film to the body, while short- 120 circuiting is prevented.

8. A thermic telephone comprising a sup- 120 port composed of a metallic body and a sur- face coating which is a fair conductor of heat but a poor conductor of electricity, and a 125 delicate heating conductor which in substan- tially its entire length is engaged and sup- ported by said surface coating.

In testimony whereof I have signed this specification.

ROBERT AERNOUT BARON VAN LYNDEN.
